UNITED STATES PATENT OFFICE.

JOSEPH W. VAUGHN, OF SALEM, MASSACHUSETTS, ASSIGNOR TO THE VAUGHN MOROCCO MACHINE COMPANY, OF PORTLAND, MAINE.

MACHINE FOR WHITENING OR WORKING LEATHER.

SPECIFICATION forming part of Letters Patent No. 444,164, dated January 6, 1891.

Application filed April 30, 1890. Serial No. 350,050. (No model.)

To all whom it may concern:

Be it known that I, JOSEPH W. VAUGHN, of Salem, in the county of Essex, State of Massachusetts, have invented certain new and useful Improvements in Machines for Whitening or Working Leather, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved machine; Fig. 2, a central vertical longitudinal section of the same; Fig. 3, a vertical transverse section taken on line $x-x$ in Fig. 1; Fig. 4, a similar view taken on line $y-y$ in Fig. 1, and Fig. 5 a sectional view taken on line 200 in Fig. 2.

Like letters and figures of reference indicate corresponding parts in the different figures of the drawings.

My invention relates especially to machines for whitening or working leather during the process of manufacture; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the frame of the machine, which consists, primarily, of two parallel vertically-arranged end pieces or standards b , secured to a bed-plate d and connected at their tops by a cross-tie f . Each standard b is provided with a horizontally-arranged arm g , projecting from the front thereof, said arms being connected at their tops by a brace h . A central circular opening i is formed in each standard b , and a tri-arm brace j is secured across said opening. A large gear k is disposed in each opening i , and is secured to the tri-arm brace j by bolts l . A horizontal stub-shaft m projects centrally through each opening i and is journaled in bearings p on the braces j , said shafts being in alignment and passing respectively through

the hubs q of the gears k . A wheel B is keyed to the inner end of each shaft m , the hubs r of said wheels being elongated and projecting into or through the hubs q of the gears k , 55 in which they work, as shown in Fig. 3. A horizontally-arranged shaft t , parallel with the shafts m , is journaled in sleeves v , secured in boxes z on the wheels B by means of set-screws 15, as best shown in Fig. 3, said sleeves 60 forming crank-pins for connecting-rods D , hereinafter described. To each end of the shaft t a pinion 16 is keyed, said pinions respectively meshing with the gears k . A pulley 17 is mounted on the shaft t at the inner 65 end of each sleeve v , and pivoted by one end on each of said sleeves between the adjacent pulley 17 and the box z there is a longitudinally-arranged connecting-rod or crank-lever D . A shoulder 18, formed on the sleeves between each rod D and the adjacent box, prevents longitudinal movement of the shaft. 70

A horizontally-arranged main shaft C is journaled in the lower portion of the frame A on the front legs of the standards b and 75 bears a centrally-arranged sprocket-wheel 20 (see Fig. 3) and a similar sprocket-wheel 21 at each end. A fast pulley 22 and loose pulley 23 are disposed on an outer end of said shaft. A large sprocket-wheel 24 is mounted 80 on the outer end of each stub-shaft m , said wheels being respectively connected by a jack-chain 25 with a sprocket 21 on the shaft C . On each body-arm g a longitudinally-arranged horizontal track or way 26 (see Fig. 85 2) is disposed, said ways being adjustable vertically by set-screws 27, passing through lugs 28 on said arms. Openings or slots 190 are formed in the frame-arms g and ears 120 on the ways 26 (see Figs. 4 and 5) project 90 through said slots. Set-screws 122 work in lugs 123 on the outer side of the arms g and engage said ears, preventing lateral tilting of the ways. A cross-sectional V -shaped oil groove or duct 121 is formed in the upper face 95 of each way.

A cross-head or roll-carriage F consists of two vertical arms 29, connected by a bar 105 and having their upper ends forked (see Fig. 4) and fitted to slide on the ways 26. A horizontally-arranged shaft 30 is fitted to rotate 100 in the lower ends of the carriage-arms 29. A

centrally-disposed whitening-roll II is secured on said shaft and is provided at each end with a hub 31, said hubs serving as pulleys over which belts 32 pass, connecting them with the 5 pulleys 17 on the pinion-shaft *t*, whereby said roll is driven. The forward ends of the connecting-rods D work on the bearings of the shaft 30, as shown in Fig. 4. The lower section of the belts 32 pass over centrally-disposed guides or tension-pulleys 33, connecting said rods *g*. A horizontally-arranged worm grinder 100, of ordinary construction, is mounted on the connecting-rod D in contact with the blades of the whitening-roll H.

15 A bench or table K is disposed in front of the machine below the arms *g*, said bench comprising vertical metallic legs 34, supported in bases 35, the side legs being respectively connected at the top by side bars 36. Two horizontal bars 50 and 51 connect each set of legs 34, and are fitted to slide vertically thereon. Levers 53 and 54, pivoted together and respectively to said bars, form toggle-joints between them. The central pivots of said joints 25 are connected by horizontal rods 55, said rods at opposite sides of the bench being connected by a cross-bar 56. Adjusting-screws 60 pass through openings in the bars or side rails 36 and work in the sliding bars 50 of 30 the bench, said screws being provided with hand-wheels 61, whereby the position of the bars in relation to said rails may be regulated and the action of the toggle-joints on said bars determined. The upper ends of corresponding screws 60 at each side of the bench are connected by flat metallic bars 57, which support a centrally-arranged horizontal bed 40, provided with a flexible covering 42 and disposed in position to be engaged by the whitening-roll H. Short laterally-arranged bars 37 are mounted on the side rails 36, at each side of the bed and support leaves 41, which form the table proper of the bench. A horizontal laterally-arranged shaft 62 is journaled in 45 bearings on the base of the bench near the rear thereof and bears a sprocket-wheel 63 of the same size as the sprockets on the stub-shafts *m*. A jack-chain 64 connects said wheel with the central sprocket 20 on the 50 main shaft C. A smaller sprocket-wheel 65 is mounted on the shaft 62. A shaft 66, parallel with the shaft 62, is mounted on the base of the bench near its front end and bears a sprocket-wheel 67, connected by a 55 jack-chain 68 with the sprocket 65 on the shaft 62. A treadle-lever 70 has one end pivoted centrally on the shaft 62, said lever projecting outward to the front of the bench, where it is provided with a foot-plate 71. A 60 vertical spindle or rod 72 is mounted in a step on the floor and a bracket 73 on the cross-bar 37 of the bench. Said spindle passes through the outer end of the treadle, and is provided at its top with a hand-wheel 65 74 and at its lower end with a nut for determining the stroke of the treadle. A chain 75 passes over a pulley 76 and connects the

treadle with the toggle-bars 55. On each bench-shaft 62 and 66 cams 80 are mounted, said cams being in engagement with the lower 70 sliding bars 51, which are actuated thereby.

In the use of my improvement, power being applied to the main shaft C, the stub-shafts *m* and bench-shafts 62 and 66 are driven conjointly thereby at the same rate of speed and in the same direction. The large wheels or disks B, keyed on said stub-shafts, are rotated thereby. The shaft *t*, journaled in the boxes *z*, fixed on said disks, is carried thereby, and the pinions 16 on said shaft, traveling on the fixed gears *k* in the frame, rapidly rotate said shaft *t*. The pulley 17, carried by said shaft and belted to the whitening-roll II, as described, rapidly rotates said roll. As the disks or wheels B revolve, the crank levers or beams D, pivoted on the shaft *t* and to the bearings of the whitening-roll II, reciprocate the roll-carriage F on its ways 26. The parts being in the position shown in the drawings, as the roll-carriage is driven forward on its ways it is out of contact with the bed 4. The leather being disposed on the bed, as the roll-carriage begins to recede or is drawn backward by the crank mechanism the operator depresses the treadle 70, drawing 95 forward the toggle-joints and forcing the sliding bars 50 and 51 apart. The cams 80 on the bench-shafts, coming into contact with the lower bar 51, conjointly act to force said bar upward, raising the bed 40 and forcing the leather into contact with the revolving roll, which operates thereon during the complete return of the carriage. The cams 80 are so constructed that they hold the bed evenly in its elevated position until the roll 100 II nearly reaches the inner end of said bed, when the cams permit the rapid fall of said bed to its normal position. The tension of the table against the roll may readily be adjusted by the screws 60. The roll may be of any suitable construction; but I deem it preferable to employ the form shown, in which the working-face is provided with centrally-diverging branched cutting-blades. The sleeves or crank-pins *v*, which also serve as 105 bearings for the pinion-shaft *t*, being adjusted radially in relation to the crank-disks B permits gears and pinions of different sizes to be substituted for the gears *k* and pinions 16, whereby the speed of said shaft *t*, and hence 110 of the whitening-roll II, may be greatly increased, if desired.

I do not confine myself to using two fixed gears *k* and two pinions 16 or to connecting more than one of the stub-shafts to the main shaft, as the shaft *t* may be rotated by means of one pinion and gear and the disk on the opposite stub-shaft be caused to rotate by said shaft as it travels.

Having thus explained my invention, what 130 I claim is—

1. In a leather-machine, the combination of a carriage, a sun-gear, a shaft, a crank-disk on said shaft, a tubular crank-pin on

said crank-disk, a rotary revolving shaft supported at one end in said tubular crank-pin and having a suitable bearing at the other end, a planetary pinion on said rotary revolving shaft meshing with said sun-gear, a pitman connecting said crank-pin with said carriage, a pulley on said rotary revolving shaft, a belt connecting said pulley with a pulley on the carriage, and a leather-supporting table beneath said carriage, substantially as described.

2. In a leather-working machine, the combination of a reciprocating tool-carriage and

a bench for supporting the leather, consisting of upright standards, frames one above the other adapted to slide vertically on said standards, a bed supported on the upper frame, toggle-levers connecting said frames, a treadle mechanism for actuating said toggle-levers to adjust the bed, and cams actuated by the driving mechanism for raising and lowering the bed at regular intervals.

JOSEPH W. VAUGHN.
